UNITED STATES PATENT OFFICE.

UTLEY WEDGE, OF ARDMORE, PENNSYLVANIA.

MIXING APPARATUS.

1,116,182.

Specification of Letters Patent.

Patented Nov. 3, 1914.

Application filed December 27, 1912. Serial No. 738,853.

To all whom it may concern:

Be it known that I, UTLEY WEDGE, a citizen of the United States, residing in Ardmore, Pennsylvania, have invented certain 5 Improvements in Mixing Apparatus, of which the following is a specification.

The object of my invention is to provide simple and effective means for mixing different kinds or qualities of pulverized, granular or lumpy material such, for instance, as different kinds of ore intended to form a charge for a furnace, such material being hereinafter referred to as "granular." This 10 object I attain in the manner hereinafter set forth, reference being had to the accompanying drawings, in which—

Figure 1 is a view, partly in longitudinal section and partly in elevation, of a mixing device constructed in accordance with my 20 invention; Fig. 2 is a transverse section of the same on the line *a—a*, Fig. 1; Figs. 3, 4, 5 and 6 are longitudinal sections illustrating different modifications of one of the features of the invention; Fig. 7 is a horizontal 25 section on the line *b—b*, Fig. 2, and Figs. 8 and 9 are sectional views illustrating a preferred construction of one of the elements of the machine.

In Figs. 1 and 2 of the drawings, 1 represents a feed hopper, or the lower portion of a feed hopper, and 2 a segregating hopper, bin or container below the same, this member of the mixing device being hereinafter, for convenience, referred to as a hopper. 30 The lower end of the hopper 2 discharges laterally, through an opening 14, onto a horizontal shelf 13 and with the latter cooperates an endless conveyer 3 carrying a succession of flights 12, said conveyer delivering the material from the shelf 13 into a bin or hopper 4. The hopper 2 is divided by a series of vertical partitions 5, 5^a, into a plurality of groups of relatively narrow chambers, two of these groups of chambers 45 being shown in the present instance, the chambers of one group being numbered 6 and those of the other group being numbered 7 and a chamber of one group alternating with a chamber of the other group throughout the length of the hopper 2, as 50 shown in Fig. 1. The partitions 5 are carried by a plate 20 mounted upon the inner side of the front plate of the hopper 2 and the partitions 5^a are carried by a plate 21 55 mounted upon the inner side of the back of the hopper, either or both of these plates being laterally movable so that the parti-

tions can be moved from or toward each other in order to vary the relative capacity of the chambers 6 and 7 and the relative 60 volume of each kind of material kept in storage in the hopper 2. In the present instance both of the plates 20 and 21 are laterally adjustable, each plate having two pairs of laterally spaced nuts 22 passing 65 through slots in the front or back plate of the hopper, each pair of nuts receiving a screw stem 23 which is free to turn in bearings 24 and is provided with a sprocket wheel 25, one pair of nuts and the screw 70 stem and sprocket wheel 25, one pair of nuts and the screw stem and sprocket wheel co-operating therewith, being spaced vertically apart from the other pair, as shown in Fig. 2, and the two sprocket wheels being 75 connected by an endless chain 26 running over an intermediate idler or idlers 27 whereby both of the screw stems 23 can be operated in unison in order to move the plate 20 or 21 in one direction or the other. 80

Co-operating with the opening 14 is a vertically adjustable valve 15 on the front of the hopper 2 and said valve 15 carries series of supplementary valves 30, one for each of the chambers 6 and 7 of the hopper, these 85 valves 30 being vertically adjustable on the main valve 15 so that the area of outlet from the chambers 6 can be regulated independently of the area of outlet from the chambers 7 and the volume of discharge of 90 one kind of material thus governed independently of the volume of discharge of the other kind of material, depending upon the desired proportions in the mixed mass.

The hopper 1 has a valved bottom, the 95 valves 8 alternating with spaces 9, whereby, when the hopper 1 is in one position, the valves 8 will prevent access from said hopper to the chambers 6 of the hopper 2 and will permit access to the chambers 7 thereof, as shown in Fig. 1, movement of the hopper 1, however, to the proper extent changing the relation of its valves and spaces to the chambers of the hopper 2 so as to cause the valves to prevent access to 105 the chambers 7 of the latter and permit access to the chambers 6. The hopper 1 is provided with wheels 10 running upon suitably mounted rails 11 so that ready shifting of the same from one position to the other 110 can be effected.

In operation of the apparatus the hopper 1 is set so that its valves 8 close the upper ends of the chambers of one group, say the

chambers 6, and pulverized or granular material of one kind is then shoveled or otherwise fed into said hopper 1 and fills the chambers 7 of the other group in the 5 hopper 2. The hopper 1 is then shifted and powdered or granular material of another kind is supplied thereto and is fed to the chambers 6 of the hopper 2, which are filled in the same way as the chambers 7 were for- 10 merly filled. The valves 15 and 30 being properly adjusted, the material flows later- ally from the lower portion of each of the chambers 6 and 7 onto the receiving shelf or platform 13 and the flights 12 of the con- 15veyer 3 move said piles along over the shelf and during such movement mix the contents of the piles so that in the mass which ac- cumulates in the hopper 4, or is directed thereby to a suitable pile, particles of one 20 kind of material are intimately commingled with particles of the other kind of material throughout the mass. Owing to the relatively narrow dimensions of the chambers 6 and 7 and to the relatively small area of 25 outlet from each chamber the units of each material flowing from the chambers 6 and 7 onto the shelf 13 are of relatively small volume and are closely juxtaposed, conse- 30 quently an intimate admixture of the differ- ent kinds of material in the storage pile or bin must necessarily take place even without the use of the conveyer 3, for supposing that the streams of material each of relatively contracted volume, flowing from the 35 chambers 6 and 7 were permitted to fall directly from the hopper 2 onto the stor- age pile, these streams, being disposed closely side by side, would be commingled during their fall, or in their spread after 40 striking the pile, and the desired intimate admixture of the different kinds of material would thus be insured. The flow of material from the chambers 6 and 7 of the hopper 2 continues until said chambers are emptied, 45 or the supply, first of one kind of material to the chambers of one group and then of the other kind of material to the chambers of the other group, may be kept up during the time that said chambers are discharging, in 50 case a continuous run of the apparatus for any considerable length of time is desired.

The means for directing the material to the different chambers of the segregating hopper may be varied in many ways without departing from the essential feature of my invention, and in Figs. 3 to 6 I have shown a number of modifications of this feature of the invention.

In the construction shown in Fig. 3 the 60 hopper 1 is stationary and a wheeled truck 16, having a valved bottom, moves between said hopper 1 and the top of the segregating hopper 2.

In the construction shown in Fig. 4 the 65 fixed hopper 1 has a valved bottom between

which and the top of the segregating hop- 70 per are interposed a series of swinging blades 17 which serve to direct the material flowing through the spaces 9 either to the chambers 6 or to the chambers 7 of the hop- 75 per 2, depending upon the adjustment of said blades, the latter being connected so as to move in unison, and the entire series being operated by means of a single lever 18.

In the construction shown in Fig. 5 alter- 75 nate partitions of the hopper 2 each com- 80 prise a fixed lower section and a pivoted upper section, said pivoted upper sections being swung as a unit by means similar to those employed for swinging the deflecting blades 17 of Fig. 4, so as to cause either group of chambers to receive material from the hopper 1.

In the construction shown in Fig. 6 a 85 fixed hopper 1 having a valved bottom is used, and the entire segregating hopper 2 is mounted upon a wheeled truck 19 so that it can be moved back and forth beneath the hopper 1 and either group of chambers 90 therefore caused to register with the valves 8 or the spaces 9 of the bottom of said hopper 1.

Although I have shown and described a segregating hopper containing but two groups of chambers the number of groups 95 may, when the partitions bear a fixed relation to one another, be increased, depending upon the number of different kinds of material which are to constitute the mixed mass. The valved bottom of the feed hopper lends 100 itself well to such multiplication of groups of chambers, the only modification neces- 105 sary being to increase the width of the valves while still retaining the single chamber width for the spaces, thus in a segregating 110 hopper having three groups of chambers the valves 8 will each be of the width of two chambers, in a hopper having four groups of chambers the valves 8 will each be of the width of three chambers, and so on. 115

By varying the relative width of the chambers in the different groups in the hop- 115 per 2, or by varying the area of outlet from the chambers of one group independently of the area of outlet from the chambers of an- 120 other group, or by the use of both of these means, any desired proportion of either of the materials to be mixed may be provided in the final mixture.

In order to insure the complete discharge 120 of material from the hopper 1 the valves 8 may be of inverted V-shape, as shown for instance at 8^a in Fig. 8, or may be provided with inverted V-shaped plates or blocks, as shown at 8^b in Fig. 9, so as to provide no 125 surfaces upon which material can find lodg- 130 ment.

I claim:

1. The combination, in a mixing appa- 130 ratus for granular material, of a segregating

hopper having groups of chambers therein, the chambers of one group alternating with those of another group, means for supplying material first to the chambers of one group 5 and then to the chambers of another group in said hopper and means for discharging material simultaneously from adjoining chambers of a plurality of groups.

2. The combination, in a mixing apparatus for granular material, of a segregating hopper having groups of chambers therein, the chambers of one group alternating with those of another group, valve mechanism whereby material may be directed to 10 the chambers of one group while the chambers of another group or groups are cut off therefrom and means for discharging material simultaneously from adjoining chambers of a plurality of groups.

20 3. The combination, in a mixing apparatus for granular material, of two members, namely a segregating hopper having groups of chambers therein, the chambers of one group alternating with those of another group, a valve structure for cutting off the supply of material to the chambers of one group while admitting it to the chambers of another group, one of said members being movable in respect to the other 25 so as to vary the relation of the valve structure to the groups of chambers in the hopper and means for discharging material simultaneously from adjoining chambers of a plurality of groups.

35 4. The combination, in a mixing apparatus for granular material, of a segregating hopper having groups of chambers therein, the chambers of one group alternating with those of another group, means for independently supplying material to the groups of chambers, and means for simultaneously discharging material from adjoining chambers of a plurality of groups.

40 5. The combination, in a mixing apparatus for granular material, of a segregating hopper having groups of chambers therein, the chambers of one group alternating with those of another group, means for independently supplying material to the groups of chambers, means for simultaneously discharging material from adjoining chambers of a plurality of groups, and means for regulating the discharge from the chambers of one group independently of the discharge 45 from the chambers of another group.

55 6. The combination, in a mixing apparatus for granular material, of a segregating hopper having groups of chambers therein, the chambers of one group alternating with those of another group, means for independently supplying material to the groups of 60 chambers.

chambers, means for simultaneously discharging material from adjoining chambers of a plurality of groups, and means for regulating the size of the chambers of one group in respect to the chambers of another group. 65

7. The combination, in a mixing apparatus for granular material, of a segregating hopper having groups of chambers therein, the chambers of one group alternating with the chambers of another group, means for independently supplying material to the groups of chambers, means for simultaneously discharging material from adjoining 70 chambers of a plurality of groups, and means for independently regulating the area of discharge from the chambers of each group.

8. The combination, in a mixing apparatus for granular material, of a segregating hopper having groups of chambers therein the chambers of one group alternating with the chambers of another group, means for independently supplying material 80 to the groups of chambers, means for simultaneously discharging material from adjoining chambers of a plurality of groups, and means for conveying said discharges away from the points of discharge. 90

9. The combination, in a mixing apparatus for granular material, of a segregating hopper having groups of chambers therein, the chambers of one group alternating with those of another group, means for feeding material to said groups of chambers independently of one another, means for simultaneously discharging the material from adjoining chambers of a plurality of groups in a lateral direction onto a receiving shelf, 100 and means for removing said discharged material from said shelf. 95

10. The combination, in a mixing apparatus for granular material, of a segregating hopper having groups of chambers therein, the chambers of one group alternating with those of another group, means for supplying material to said groups of chambers independently of one another, means for laterally discharging the material from 105 adjoining chambers of a plurality of groups onto a receiving shelf, and an endless conveyor operating above said shelf and serving to remove the material therefrom. 110

In testimony whereof, I have signed my 115 name to this specification, in the presence of two subscribing witnesses.

UTLEY WEDGE.
